UNITED STATES PATENT OFFICE.

MICHAEL I. RODRIGUE, OF SAN FRANCISCO, CALIFORNIA.

ELASTIC SOCKET FOR PEN-HOLDERS.

SPECIFICATION forming part of Letters Patent No. 413,092, dated October 15, 1889.

Application filed March 29, 1888. Serial No. 268,763. (No model.)

To all whom it may concern:

Be it known that I, MICHAEL I. RODRIGUE, a citizen of the United States, residing in the city and county of San Francisco, in the State 5 of California, have invented certain new and useful Improvements in Elastic Sockets for Pen-Holders; and I do hereby declare that the following is a full, clear, and exact description of my said invention, reference being had to the drawings that accompany 10 and form part of this specification.

My invention relates to improvements in grips or sockets for fixing pen-points to handles or holders; and it consists in the production of a socket capable of adjusting itself to different sizes and shapes of pen-points, and of clamping or holding the same firmly, and also possessing the property of imparting a certain elasticity to the pen-point when 15 in use.

The nature of my said improvements and the manner in which I proceed to construct and produce my elastic socket for pen-holders are fully explained in and by the following 20 description, reference being had to the accompanying drawings by letters and figures.

Figure 1 represents the complete socket and holder with the pen-point set ready for use. Fig. 2 shows the socket with the soft-rubber sleeve taken off. Fig. 3 is a view of the socket complete, but with the soft-rubber part broken away. Figs. 4 and 5 show the inner or metallic part of the grip. Fig. 6 is a sectional view through the butt-end of the 25 stock or handle before the grip is fitted to it. Fig. 7 is the soft-rubber sleeve or outer part of the grip.

Similar letters of reference indicate like parts in all the figures of the drawings.

40 This improved socket for pen-point is composed of an inner split sleeve or barrel of metal, and an outer and surrounding tube of soft rubber fitting closely over the metal part, and, by virtue of its elastic qualities, 45 compressing or drawing the metal sleeve together upon the wooden portion or stock of the holder, the end portion of the holder being turned off of cylindrical shape and of suitable diameter to take the metal sleeve.

50 A is the inner sleeve of metal; B, the outer soft-rubber tube surrounding it, and C the stock or handle. The part A is formed of

sheet-brass or other material having sufficient spring and stiffness to maintain its shape by bending a strip of suitable width and length 55 around a mandrel, or by cutting it from a length of tubing. Slits a^x a^2 are made at one end running longitudinally toward the other end of the sleeve, and one of them is carried the full length, so that it divides the 60 tube from end to end. The butt-end of the stock or handle portion C is turned down to a smaller diameter and of suitable thickness to take the metal sleeve, these two parts being so proportioned that the metal fits closely 65 and smoothly on the stock. The part B, fitting over and surrounding this sleeve, is made of soft-rubber tubing, such as can readily be obtained of the manufacturer at the present time of various sizes and degrees of 70 thickness. Tubing of one-fourth to three-eighths inch in diameter will be found to answer well for this sleeve. This rubber tube should be of such diameter internally that when drawn over the metal part A it is 75 stretched, and by its contraction is made to draw the metal part together around the stock. When properly formed and fixed, the surface of the elastic socket and the body of the handle should come flush with each 80 other, and when properly made, also, the socket will retain its place on the handle without requiring any additional fastening; but a metal band, as X, fixed over the joint where the rubber sleeve and the wood come 85 together will add to the elegance of the holder, and may also be made to confine the rubber at this point by being slightly pressed over it. In setting the pen-point in this holder, it is inserted between the metal jaws 90 of the grip, with the nib or point in line with the long slit of the sleeve, and the shank of the pen is pressed down into the socket a sufficient distance to hold it. In this position the pen-point is gripped firmly, but not 95 rigidly, and while it is held against any tendency to move laterally it is permitted to have a certain amount of elasticity under vertical pressure. When inserted in this manner under the metal sleeve, the pen-point is gripped 100 with sufficient degree of force by the contraction of the surrounding rubber; but its own inherent elasticity is not taken away or restricted, so that the normal flexibility

of the nibs and other qualities of pen-points, even of the finest kinds or grades, are not affected. The same size of socket will take in and properly hold any size and quality of pen-point, and, besides holding it always in perfect alignment with the handle, the elastic properties of the socket impart a considerable degree of flexibility to the pen and allow a freedom of action that renders the pen quite sensitive to the pressure and motions of the fingers. Under side movements and angular movements of the hand of the writer the pen-point will have no slip or loose motion; but under direct perpendicular or downward pressure it has the quality of yielding.

In addition to the above-mentioned qualities and properties that contribute to the comfort of the writer and the elegance of

handwriting, my improved socket possesses ²⁰ the advantages of low cost of manufacture and great durability.

Having thus fully described my invention, what I claim, and desire to secure by Letters Patent, is—

In a pen-holder, the combination, with the butt or handle portion C of the stock, of a split sleeve A, of metal, surrounding the portion C, to receive the pen between it and said portion, and a soft-rubber tube B, surrounding and clamping the sleeve C, substantially as and for the purpose set forth.

In testimony that I claim the foregoing I have hereunto set my hand and seal.

MICHAEL I. RODRIGUE. [L. S.]
